UNITED STATES PATENT OFFICE.

LOUIS ROMMEIKS, OF NEWARK, NEW JERSEY.

DESIGN FOR ORNAMENT ON HARNESS-SADDLES.

Specification forming part of Design No. 5,191, dated August 8, 1871.

To all whom it may concern:

Be it known that I, LOUIS ROMMEIKS, of Newark, county of Essex and State of New Jersey, have invented and produced a new and original Design or Ornament for Harness-Saddles, of which the following is a specification:

The nature of my design is fully represented in the accompanying drawing, which illustrates a portion of a harness-saddle and my invention; and it consists in placing between the rein-guides and immediately over the tight-rein hook an arch surmounted by a stationary ring containing a fly, the contour of the fly-ring corresponding to the contour of the rein-rings. And, as use may be combined with ornament, this ornamentation of the harness-saddle prevents disengagement of

the tight-rein with the hook, on the horse throwing up his head.

Figure 1 is an elevation; Fig. 2, a top view; Fig. 3, a sectional plan; and Fig. 4, a sectional elevation.

In the drawing, A indicates a portion of a harness-saddle; B, the tight-rein hook; C, the tight-rein; and D D, the long-rein guides. E is the arch; F, the fly-ring; and G, the fly.

I claim as my invention—

The design E F G, as shown and described, for an ornament on harness-saddles.

LOUIS ROMMEIKS.
